UNITED STATES PATENT OFFICE.

JOHN MORRISON CAMPBELL, OF LOMBARD, ILLINOIS.

STAMP.

No. 827,347.

Specification of Letters Patent.

Patented July 31, 1906.

Application filed August 1, 1905. Serial No. 272,156.

To all whom it may concern:

Be it known that I, JOHN MORRISON CAMPBELL, a citizen of the United States, and a resident of Lombard, in the county of DuPage and State of Illinois, have invented a new and Improved Stamp, of which the following is a full, clear, and exact description.

This invention relates to hand-operated stamps such as found upon desks in offices for the purpose of affixing dates or other printed matter to papers or envelopes.

The object of the invention is to provide a stamp of this class with an improved inking device, to the end that the stamp or type may be inked quickly, neatly, and thoroughly and so that a distinct and uniform impression will be produced.

Reference is to be had to the accompanying drawings, forming a part of this specification, in which similar characters of reference indicate corresponding parts in all the views.

Figure 1 is a side elevation of a stamp to which my invention has been applied. Fig. 2 is a section taken substantially upon the line 2 2 of Fig. 3. Fig. 3 is a vertical transverse section taken upon the line 3 3 of Fig. 1. Fig. 4 is a plan view of the inking-pad, certain parts being represented as broken away or shown in section; and Fig. 5 is a transverse section through the pad and its contiguous parts, taken substantially upon the line 5 5 of Fig. 4.

Referring more particularly to the parts, 1 represents the frame of the stamp, which 35 comprises a pair of oppositely-disposed side plates or legs 2, which support a pad box or casing 3, preferably formed integrally therewith, as illustrated. From the upper side of the pad-casing 3 a tubular guide 4 projects vertically, as shown, and upon this 40 guide there is slidably mounted a handle 5, which telescopes therewith in a common manner, the helical spring 6 being mounted within the guide 4, which affords means for 45 normally maintaining the handle 5 in an elevated position in a well-known manner. To the lower extremity of the handle 5 a yoke 7 is attached, which is formed with vertically-dependent arms 8, and between these arms a 50 horizontal pin 9 extends, the said pin passing through vertical guide-slots 10, formed in the aforesaid side plates 2. Upon the pin or shaft 9 a carriage 11 is mounted, the body 12 whereof receives a backing-block 13 for a 55 printing-plate 14. At its extremities the car-

riage 11 is formed with downwardly-projecting wings 15, which are provided with cam-grooves 16, as shown. These wings lie adjacent to the inner faces of the side plates 2 and coöperate with the usual pins 17, so as to invert the carriage as the handle 5 is depressed in a well-known manner. From this arrangement it will be seen that the spring 6 normally operates to maintain the printing-plate 14 against the face of a pad 18, which is 60 mounted in the pad-casing 3, as shown. This pad 18 is preferably formed of a facing-sheet of some absorbent material, such as felt. This facing-piece is received against a backing or grid 19. This grid consists of a plate 70 of any material, but preferably of plate-steel or similar material, provided with a plurality of slots, grooves, or perforations 20, as shown. The edges of this plate 19 are preferably bent inwardly, so as to form flanges 21, the inner 75 edges whereof rest against the upper wall of the casing 3, as illustrated. In order to insure that the pad 18 will be retained in a position against the backing plate or grid 19, I provide a retainer 22. This retainer preferably consists of a resilient wire bent into a rectangular shape conforming to the interior of the casing 3. When the parts are assembled, this retainer has a relative position, (illustrated most clearly in Figs. 4 and 5,) constituting 80 a binding around the edge of the pad. This retainer of course tends by its own resiliency to expand, and this affords means for holding it in position when so placed.

From the arrangement described it will be 90 seen that by reason of the flanges 21 at the back of the grid 19 a chamber 23 is formed within the casing 3. This chamber enables the pad to be supplied with ink in a convenient manner. For this purpose the upper 95 wall of the casing 3 is preferably punched upwardly when it is formed, so as to provide a nipple 24, the same being provided with an opening through which the ink may be introduced.

As indicated most clearly in Figs. 4 and 5, the part of the grid 19 beneath the nipple 24 is not provided with the perforations 20. In this arrangement when the ink falls upon the plate it spreads in all directions and seeps 105 gradually through the perforations at different parts of the plate. In this way the ink becomes very well distributed before being absorbed by the pad. This arrangement conduces very much toward producing a uni- 110

formity in the impression from the plate 14, overcoming effectually the usual effect of blurring following immediately upon the re-inking of the pad. Furthermore, the effect 5 of reinking the pad in the manner suggested is much prolonged by the device described.

In order to prevent the hand of the person operating the handle 5 from coming into contact with the nipple 24 when the handle is depressed, I provide a laterally-projecting ear 26, which is integral with the body of the yoke 7 extending therefrom, as shown. This ear 26 lies directly above the nipple 24 and when the handle is depressed constitutes a 15 covering for the nipple which effectively prevents one's fingers from coming into contact with the nipple, as will be readily understood.

Having thus described my invention, I

claim as new and desire to secure by Letters Patent—

In a stamp in combination, a casing having an opening in the upper side thereof through which ink may be introduced, a pad within said casing, a printing-plate normally held against said pad, and a depressible handle adapted to actuate said printing-plate and having a laterally-projecting ear adapted to cover said opening when said handle is depressed.

In testimony whereof I have signed my name to this specification in the presence of two subscribing witnesses.

JOHN MORRISON CAMPBELL.
